UNITED STATES PATENT OFFICE.

EARL H. RICHARDSON, OF ONTARIO, CALIFORNIA, ASSIGNOR TO PACIFIC ELECTRIC HEATING COMPANY, OF ONTARIO, CALIFORNIA, A CORPORATION OF CALIFORNIA.

ELECTRIC LAUNDRY-IRON.

No. 900,208.

Specification of Letters Patent.

Patented Oct. 8, 1908.

Application filed December 2, 1907. Serial No. 404,873.

To all whom it may concern:

Be it known that I, EARL H. RICHARDSON, a citizen of the United States, residing at Ontario, in the county of San Bernardino 5 and State of California, have invented new and useful Improvements in Electric Laundry-Irons, of which the following is a specification.

This invention relates to electric laundry irons such, for example, as shown and described in a former patent of mine, No. 866,810, issued September 24, 1907, and the objects of the present invention are to improve the construction.

15 The distinguishing feature of the present application consists in providing means for automatically breaking the electric circuit through the heating element of the iron when the temperature of the iron rises to a certain point, whereby electricity is conserved and damage from overheating avoided.

The automatic circuit opening device employed consists of a thermic fuse, and one of the main points of novelty and advantages 25 of the present construction over the former is that instead of securing the fuse supports to the lower member of the laundry iron, I mount the same independently of the lower member and of the cover; and instead of 30 mounting the terminals, which are brought into contact with the fuse terminals, on the cover, I mount them on the lower member, whereby the cover carries none of the interior parts of the iron and may be readily removed without disturbing any of the interior mechanism of the iron, and the inspection or renewal of parts may thus be effected with greater ease and rapidity.

In the former construction, in order to 40 secure perfect connection through the fuse or fuses, it was necessary to accurately place the cover in exact position on the lower member of the iron, and to secure such accurate position a special construction was 45 necessary, which is avoided in the present construction, and the cover may be screwed or otherwise fastened to the lower member without requiring any greater nicety of fit than is consistent with the grade of construction desired.

Another object is to so mount the fuse and its support that it may, upon removing the cover, be removed at once from the interior of the iron.

55 Another object is to employ but a single

fuse, while in the former case two fuses were employed.

Other objects and advantages relate to details of construction which will be herein pointed out.

Referring to the drawings:—Figure 1 is a plan view of the laundry iron with the cover removed. Fig. 2 is a longitudinal vertical cross section through the laundry iron, with the cover in place, on line x^2-x^2 Fig. 1. Fig. 3 is a perspective in detail of the fuse and fuse support. Fig. 4 is a cross section through a heating unit on line x^4-x^4 of Fig. 1.

1 designates the lower member of the iron 70 which is formed hollow as shown, with lower heating wall or sole, and provided in the toe with an extra metal portion 2, and in each heel corner with extra metal portions 3. The toe portion 2 is provided with 75 two vertical circular cavities, and each heel portion 3 is provided with a single vertical circular cavity, and two heating units 4 are angularly disposed diverging toward the rear, their front ends being in the cavities 80 in the toe portion 2 and their rear ends being in the respective cavities in the heel corners 3. Each heating unit 4 comprises a central core 5 formed preferably of a good heat conducting material such as copper, 85 each core having tongues 6 which project into slotted plugs 7 which are snugly seated in the cavities referred to. The plugs 7 are also preferably formed of good heat conducting material and as indicated in Fig. 90 4 the upper end of each plug 7 is upset to lap over the upper edge of the adjacent tongue 6 of the core 5 so that the cores are thus securely held in position, the tongues 6 being wedged between the members of each 95 plug in addition to the upper ends of the plugs being hammered over the tongues. Mica 8 is wound over each core 5 and resistance wire 9 is then coiled around over the mica 8, with its coils separated to prevent 100 short circuiting. As shown in Fig. 4, the heating unit thus formed is substantially triangular in cross section, and its lower flat face rests upon a strip of mica 10 laid next to the lower member 1, the mica 10 keeping the wire 9 out of contact with the metal forming the lower member 1. While the heating units 4 are thus rigidly and firmly secured in position, it is obvious that they 105 may readily be removed, if desired, by 110

slightly chipping the upturned ends of the plug 7. At the front end, as shown in Fig. 1, wires 11 and 12 lead back through the hollow open space between the two heating units 4. The mate of wire 12 is united with wire 12 as at 13 and the mate of wire 11 is united with wire 11 as at 14.

A fuse receptacle is formed between the two heating units 4 by means of bowed 10 sheets of mica 15 united at the back by transverse mica sheets 16, and the body portion of mica sheets 15 are slotted to permit the wires 11 and 12 to pass therethrough. Arranged within the fuse receptacle thus 15 formed is a fuse support comprising a table 17 having two downturned flanges 18 and tapering edges 19 which permit the table to fit the slanting side wall of the mica sheets 15. Two terminals 20 and 21 are mounted 20 on the table 17, each comprising a central bolt 22 which passes through an enlarged perforation 23 in the table 17 so that the shank of the bolt does not come in contact with the table. Interposed between the 25 head of the bolt and the underside of the table is a mica washer 24. A mica washer 25 is arranged above the table 17 and a metal washer 26 is above the mica washer 25, there being a nut 27 screwed on bolt 22 30 above washer 26, and a washer 28 above nut 27, one wire 11 being fastened to bolt 22 of terminal 20 between nut 27 and washer 28, the other wire 12 being similarly fastened to terminal 21. Above washer 28 is a nut 29, 35 and extending between the two terminals 20 and 21 above nuts 29 is a thermic fuse comprising a thin plate of fusible metal, and holding the fuse 30 in place are nuts 31 screwed on the respective studs 22.

40 It will be noted that when the cover is in place, the fuse and its support are completely housed from the other parts of the iron by the mica sheets 15 and 16 and by the mica layer 39 which is surmounted by a 45 thick asbestos layer 32 above which is a cover 33, the latter being secured to the lower portion 1 of the iron by screws 34.

It will be noted that the circuit between 50 wires 11 and 12 is completed through the fuse 30. The rear wires from each unit 4 are connected to terminals 35 and 36 which project through the rear wall 37 of the lower member 1, the terminals 35 and 36 being provided with tongues 38, to which a 55 connection plug, not shown, is attached when the iron is to be used.

By removing the cover 33 and the sheet 60 of mica 39, all the parts of the iron are exposed as shown in Fig. 1, thereby permitting ready inspection of the parts and replacement of the same when necessary. Should the fuse 30 melt, the metal therefrom is kept within the fuse receptacle formed of the mica sheets 15 and 16 and thus cannot 65 come in contact with the wire of the heat-

ing units. The fuse support, terminals, and fuse, shown in Fig. 3, are unattached to the body of the iron, the table 17 merely resting upon the bottom member 1, being firmly held in position, when the top is on, by the 70 pressure of the top and intervening strips 31 and 32 upon the tops of terminals 20 and 21. Therefore, when the cover is removed, the fuse support with its terminals and the fuse may be lifted out of the iron and a 75 new fuse or other parts substituted without disturbing the other parts of the iron.

It will be seen that the fuse is perfectly supported and kept in place, closing the circuit between wires 11 and 12 irrespective of 80 the exact position of the cover of the iron. This feature is also of great advantage in manufacturing, as the fuse support and its parts may be easily assembled without having to fit the other parts of the iron thereto. 85

What I claim is:—

1. A member having a heating surface, an electrical heating unit within the member, a thermic fuse in circuit with the heating unit, and a fuse support unattached to the member 90 and supporting the fuse.

2. An electric laundry iron comprising two members, a heating unit between the members, a thermic fuse in circuit with the heating unit, and a fuse support unattached 95 to the members and supporting the fuse.

3. An electric laundry iron comprising two members, a heating unit between the members, a thermic fuse in circuit with the heating unit, and a fuse support unattached 100 to the members and supporting the fuse, the two members when in place firmly pressing the fuse support between them to hold it in place.

4. A member having a heating surface, an 105 electrical heating unit within the member, a thermic fuse in circuit with the heating unit, a fuse support unattached to the member and supporting the fuse, and a fuse receptacle of non-conducting material inclosing 110 the fuse and its support.

5. In an electrically heated device, a member having a recess, a cover therefor, a pair of electrical heating units in the recessed member, a fuse support between the heating 115 units, and a thermic fuse on said support and connected to the heating units.

6. In an electric laundry iron, a body, a pair of angularly disposed heating units therein diverging rearwardly, a fuse support 120 having inclined sides fitting between the heating units, and a thermic fuse on the fuse support connected in circuit with the heating units.

7. A thermic fuse support comprising a 125 table formed of a single piece of material having down turned flanges forming supports, binding posts on the table, and a fuse between the binding posts.

8. In an electric heating device, a recessed 130

member, a pair of electrical heating units therein, a fuse support comprising a table resting on the member, binding posts on the table, a fuse between the binding posts, one binding post being connected to one heating unit, the other binding post being connected to the other heating unit.

9. In an electrical heating unit, a member having a heating wall, an electrical heating unit within the member for heating the wall, and a thermic fuse comprising a thin flat plate in circuit with the heating unit and close to and parallel with the heating wall.

10. In an electrical heating device, a member having a heating wall, an electrical heating unit within the member for heating the wall, and a thermic fuse in circuit with the heating unit, there being a free air space around both faces of the fuse.

11. In an electric laundry iron, a recessed member, an electrical heating means therein, a removable cover for the recessed member, binding posts on the recessed member in circuit with the heating means, other binding posts in the recessed member in circuit with the heating means, and a thermic fuse between the latter binding posts.

12. In an electric laundry iron, a recessed member, an electrical heating means therein, binding posts on the member in circuit with the heating means, other binding posts in the member in circuit with the heating means, a thermic fuse between the latter binding posts, and a table within the member supporting the latter binding posts.

13. In an electric laundry iron, a recessed

member, an electrical heating means therein, binding posts on the member in circuit with the heating means, other binding posts in the member in circuit with the heating means, a thermic fuse between the latter binding posts, and a cover detachably secured to said member and unattached to the other elements.

14. In an electric laundry iron, a recessed member, an electrical heating means therein, binding posts on the member in circuit with the heating means, other binding posts in the member in circuit with the heating means, a thermic fuse between the latter binding posts, a cover detachably secured to said member and unattached to the other elements, and a lining of non-conducting material at the inner surface of the cover and pressing on the tops of the latter binding posts.

15. In an electric laundry iron, a recessed member with a rear wall, a pair of binding posts secured to the rear wall and projecting therethrough, a pair of electrical heating units within the member in circuit with said binding posts, a fuse support between the heating units and forward of said binding posts, binding posts on the fuse support in circuit with the heating units, and a thermic fuse between the latter binding posts.

In testimony whereof, I have hereunto set my hand at Los Angeles California this 9th day of November 1907.

EARL H. RICHARDSON.
